UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,270,328.

Specification of Letters Patent. Patented June 25, 1918.

Application filed February 12, 1917. Serial No. 148,056.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter returned through distributing mechanism to the magazine from which they started.
- 25 More particularly, it relates to such machines when equipped with a plurality of fonts of matrices, any one of which may be brought into action at will.

The fonts most commonly employed each 30 comprise about ninety different matrices, which vary widely in body size or thickness in the respective fonts, reaching as high as 18 pt. or more. While these regular fonts thus afford a wide choice to the compositor, 35 there are certain classes of work which require even larger sizes of matrices. To meet this requirement, it has been proposed to equip the machines with one or more supplemental magazines containing an auxiliary font or fonts of the required size 40 (which may be anywhere between 24 pt. and 36 pt. or more), or containing any other fonts desired to supplement the regular fonts of the main magazines. Ordinarily, 45 the machines are provided with a series of main magazines which are movably arranged so that any selected one thereof may be brought into operative relation to a single distributing mechanism at the top and a single assembling mechanism at the bottom, and 50 with a single supplemental magazine arranged in constant operative relation to the distributing and assembling mechanisms, or with a plurality of supplemental magazines 55 which, like the main magazines, are mov-

ably arranged so that any selected one may be brought into such operative relation.

This prior arrangement permits the free mixture of the matrices of the regular fonts with those of the auxiliary fonts, but it does 60 not allow the matrices of either the regular fonts or of the auxiliary fonts to be used or mixed with each other, as the machine is capable of distributing the matrices only into two of the magazines at a time, one a 65 main and the other a supplemental magazine.

It is one of the purposes of my invention to obviate the above disadvantage, and to provide a machine wherein the matrices of the main and auxiliary fonts, either alone 70 or conjointly, may be mixed together in the same line, thus increasing the capacity of the machine to the fullest possible extent. To this end, specifically, I store the regular and auxiliary fonts in two tandem series 75 of stationary magazines, and provide distributing mechanism which cooperates continuously with all the magazines of both series so as to distribute the matrices therewith at all times and irrespective of the 80 particular magazine or group of magazines in use. In addition, I employ two separate keyboards which may be connected to different selected magazines of the respective series so that matrices may be released 85 from any magazine or group of magazines of either or both series, assembling mechanism also being provided whereby the matrices thus released may be carried away to the usual assembler and composed in line. 90 Various other features will appear in the detailed description to follow.

In the accompanying drawings, I have shown my invention only in preferred form and by way of example and as applied to 95 the particular style of machine, and it will be understood that many changes and variations in its form, and in its mode of application, may be made and still be comprised within its spirit, generally speaking, I desire it to be understood that I do not limit myself to any specific form or adaptation, except in so far as such limitations are specified in the claims.

Referring to the drawings: 105
Figure 1 is a front view of a portion of a linotype machine having my invention applied thereto;

Fig. 1^a is a vertical section taken through the lower portion of the main magazines; 110

- Fig. 2 is a side elevation thereof looking from the right in Fig. 1;
- Fig. 3 is a section on the line 3—3 of Fig. 1;
- 5 Fig. 4 is a section on the line 4—4 of Fig. 1;
- Fig. 5 is a view of the supplemental magazine selecting keys looking up from the bottom of Fig. 4; and
- 10 Fig. 6 is a front view of the supplemental magazines showing diagrammatically their relation to the associated keyboard, etc.
- The matrices X of the regular fronts are stored in the series of main stationary magazines, A, four of which are illustrated herein, although a greater or less number may be employed. The matrices are released from a selected magazine by the manipulation of the keyboard A¹, whence they pass down or 15 through the channeled raceway or front plate A² onto the main assembling belt A³, which delivers them to the assembler A⁴ wherein they are composed in line. When the composition of the line is completed, the 20 assembler A⁴ is raised and the line transferred to the first elevator A⁵, which thereupon descends and presents it to the casting mechanism for the production of the slug. After casting, the first elevator rises to its 25 uppermost position, and the matrices then transferred onto the second elevator A⁶, which carries them upwardly into operative relation to the distributor box A⁷ into which they are pushed under spring pressure by 30 the transfer slide A⁸. From the distributor box the matrices are fed one by one and presented to the action of the so-called primary distributor B (see Fig. 2) which sorts them according to form, irrespective of character, 35 and drops them into one or another of the tubes B¹ leading to the distributors B², one for each magazine. Each distributor B² is adapted to separate the matrices delivered to it according to character and drop them 40 into the underlying one of the magazine entrances B³ connected to the respective magazines. The distributors B² are made up as usual of longitudinally ribbed or permuted bars and a set of conveying screws for propelling the matrices therealong. The parts 45 so far described are or may be the same as shown and described in my Letters Patent No. 848,771, or as embodied in the commercial Model 9 machine.
- 50 It is pointed out that the selection of one or another of the magazines A is controlled by the hand lever A⁹, shown in Fig. 1. As described in my above Letters Patent, this hand lever is connected to and is adapted to 55 operate a vertically movable frame A¹⁰, which carries at its upper end a throat or switch A¹¹ to conduct the matrices from the selected magazine to the channeled raceway A² and which also carries a series of actuating members A¹² for the escapements a of

that magazine, these actuating members serving as the medium through which the reeds A¹³ operated from the keyboard A¹ are connected to the magazines.

From the foregoing, it is apparent that any selected one of the main magazines A may at any time be brought into use by the operation of the hand lever A⁹, thus permitting the mixture of matrices from any one of the magazines or any combination thereof, it being understood that the several distributors B² remain in constant connection with the respective magazines and are thus adapted to distribute the matrices into all of them continuously and irrespective of the one in use.

The matrices X of the auxiliary fonts are stored in a second series of inclined stationary supplemental magazines C, arranged at the side of or in tandem with the main magazines A and of the same number, although not necessarily so. These supplemental magazines are of plain rectangular shape and have their grooved channels parallel throughout and more widely separated than ordinarily in order to accommodate the larger matrices which they are thus adapted to contain. To provide for the distribution of the matrices into the magazines C, the several distributors B² (see Fig. 1) are extended thereover and formed with as many additional distributing combinations as is required, further magazine entrances C¹ being employed to conduct the matrices from the extended portions of the distributors to the respective magazines. In other words, the several distributors B² are common to both series of magazines, each distributor alone serving the opposite magazines of the two series. This arrangement of the magazines and distributors is very advantageous, in that it avoids a duplication of parts which might otherwise be necessary. It is pointed out that the auxiliary matrices stored in the supplemental magazines are of the same form (except as to their character-combinations) as the regular matrices contained in the main magazines, so that both may be sorted by the primary distributor B and be delivered to the appropriate character distributor for return to their proper magazine.

Turning now to the assembling mechanism for the supplemental magazines C, it will be noted (see particularly Figs. 1 and 3) that the main assembling belt A³ is extended to the right sufficiently to coöperate with the lowermost one of the series, and that for the three remaining magazines there are as many separate endless conveyer belts F, communicating with the main belt through tubes or conductors G (Fig. 1). The belts F and the extended portion of the belt A³ are arranged one above another and disposed horizontally along the discharge 130

ends of their respective magazines in position to receive the matrices therefrom, the matrices being guided to the belts by short intermediate channeled throats E whose 5 lower walls slope downwardly at a slight angle so as to present the matrices thereto in a position approaching the vertical. Each belt has a guard plate F⁶ arranged along its forward edge to retain the matrices thereon 10 and to guide them properly as they are carried along therewith.

In order to avoid interference with the matrices and the other parts, the several conveyor belts F are so arranged that notwithstanding 15 their superposed relation, the overlying ones will be adequately spaced from the underlying ones. As shown particularly in Fig. 6, each is supported at its opposite ends upon a pair of rollers F¹ and with its 20 lower stretch passing over a second pair of guide rollers F² arranged at opposite sides of the corresponding magazine and rotating about axes which are offset from or situated slightly below the axes of the rollers F¹. As 25 thus arranged, the opposed stretches of the belts, though out of contact, are maintained in immediate proximity to each other throughout the widths of the magazines and consequently occupy the minimum of space, 30 each belt (see Fig. 3) lying substantially in the plane of its own magazine so as to receive the matrices therefrom and yet being arranged free and clear of the matrices issuing from the underlying magazine. The ex- 35 tended portion of the main belt A³ is supported in a similar manner, it being noted (Fig. 1) that the lower stretch of the belt between the main driving pulleys and the rollers F¹ is held up by an underlying pair 40 of small rollers as shown. The belts may be driven in any suitable manner. As herein illustrated, the inner roller F¹ of the main belt (which is continuously driven in the usual way) is connected by a cord-and- 45 pulley arrangement F³ to the corresponding roller of the belt F immediately above (Figs. 1 and 3) while the outer roller F¹ of the main belt is connected to the corresponding rollers of the two uppermost belts by cord-and-pulley arrangements F⁴ and F⁵ (Figs. 1 and 2).

To effect the release of the matrices from the supplemental magazines C, each is provided with a series of escapements C² actuated through a corresponding series of pivoted levers H¹ by a single series of vertical reeds H². The reeds H² are supported in suitable guideways in advance of the assembling belts F and their guard plates F⁶, 55 and the levers H¹ of each series are pivoted centrally to the under side of the corresponding throat E, passing beneath the associated conveyor belt and located above or out of the path of the matrices passing through 60 the underlying throat. As the parts are thus

arranged, the matrices are free to be delivered from any one of the magazines without interference with the escapement actuating devices and consequently may be of any size or thickness within the capacity of the 70 magazines. The reeds H² are actuated from a separate and independent keyboard H, which in the present instance has its finger keys in the form of horizontally disposed push rods H⁴, whose actuating movements 75 are imparted directly to the reeds through small pivoted bell crank levers H⁵.

In the normal condition of the parts, the escapements C² are held by springs C³ with their upper pawls in engagement with the 80 leading matrices in the magazines, the levers H¹ being held away from the escapements by attached springs H⁵ which also, due to the connection of the levers with the reeds H², maintain the latter in raised position. 85 When, however, the keys or push rods H⁴ are actuated, the reeds H² are depressed, overcoming the force of the springs H⁵ and causing the levers H¹ to rock the escapements C² against the tensions of their springs C³. 90 This action of the parts effects the withdrawal of the upper escapement pawls from the magazines and allows the leading matrices to slide forwardly until they are arrested by the lower pawls, which by the 95 same action have been projected into the magazines. Then, when the finger keys H⁴ are released, the springs C³ and H⁵ restore the parts to their former condition, effecting the withdrawal of the lower pawls to allow 100 the matrices arrested thereby to pass from the magazine, and at the same time projecting the upper pawls into the magazine to arrest the next matrices, which now become the leading ones. 105

Each of the auxiliary fonts herein employed comprises a greater number of matrices than may be stored in a single one of the supplemental magazines and it is therefore proposed to divide such font between 110 two magazines. For instance, in the drawings the upper pair of supplemental magazines is shown as containing one font of matrices, half in one and half in the other, and the lower pair of magazines as containing a second font of matrices, one half in each. Due to this division of the matrix fonts among the supplemental magazines, means are provided (as hereinafter to be described) whereby the extra keyboard H may 115 be operatively connected at will to either pair of magazines to the exclusion of the other, the parts being so arranged that the keyboard may effect the operation of the escapements of both magazines of the selected pair to release matrices from either in response to the actuation of the finger keys. 120 Assuming, for purposes of illustration, that the keyboard is connected to the upper pair of magazines and that the font con- 125 130

tained therein comprises sixty-six matrices, divided equally between them, then the number of escapements C^2 and their operating levers H^1 for each magazine must be thirty-
 5 three and that of the actuating reeds H^2 sixty-six, corresponding of course to the number of finger keys H^4 in the keyboard H . To provide for the operation of both series of escapements by the single series of reeds, the
 10 magazines of the selected pair are offset edgewise or laterally (see Fig. 6) so as to locate the escapements of the respective series in different vertical planes or in staggered relation to each other. As thus ar-
 15 ranged, the escapements of the upper magazine through their pivoted levers H^1 may be and are connected to every other one of the key-controlled reeds H^2 , while the escape-
 20 ments of the lower magazine, through their corresponding levers H^1 , may be and are connected to the intermediate reeds. In other words, the key controlled reeds are in effect divided into two alternated sets, one connected to the escapements of the upper
 25 magazine and the other to the escapements of the lower magazine. For instance, as shown in Fig. 6, the actuation of the first, third and fifth of the reeds effects the operation of the first, second and third es-
 30 capements of the upper magazine and the consequent release of the matrices bearing the characters "e", "a" and "i"; while the actuation of the second, fourth and sixth of the reeds effects the operation of the first, sec-
 35 ond and third escapements of the lower magazine and the consequent release of the matrices containing the characters "t", "o" and "n". The two magazines of the lower pair are arranged in the same manner, their
 40 respective escapements being staggered with reference to each other and connected through the pivoted levers H^1 to the alternate sets of the key controlled reeds H^2 , it being understood that for this purpose the
 45 escapements of the lower pair are located in the vertical planes of the corresponding escapements of the upper pair.

The means employed for selecting either pair of supplemental magazines will now be described. It is apparent that, unless otherwise provided for, the constant connection of the key controlled reeds H^2 to the escapements of the two pairs of magazines, as shown, would result in the release of matrices from both upon the actuation of the keyboard H . The magazines are therefore equipped with locking devices to retain the matrices therein except when needed. In the present instance, the locking devices are
 50 constituted by the well-known rock shafts J journaled in suitable bearings on the upper sides of the respective magazines and each having a lip or ledge which may be moved into or out of engagement with the
 55 matrices in the corresponding magazine to

lock them therein or to permit their release therefrom. Since the magazines are to be used in pairs, as before described, it is necessary that the matrix locking devices be correspondingly operated in pairs in selecting 70 the desired magazines, and means are provided to effect their operation in this manner, and are also provided whereby the movement of the rock shafts of one pair to unlocking or inactive position effects the 75 movement of those of the other pair to locking or active position, so as thus to permit matrices to be released from only one pair of magazines at a time.

As herein illustrated, the magazine selecting means (Fig. 4) comprise two vertical reciprocating slides M , each provided at opposite ends with two inclined or cam surfaces M^1 sloping upwardly and rearwardly and arranged in engagement with 80 rollers J^3 carried by crank arms J^2 depending from the inner ends of the rock shafts J . The rollers J^3 are maintained in engagement with the cam surfaces M^1 by torsional springs J^1 (Figs. 1 and 4) surrounding the 85 rock shafts and tending constantly to move the latter to unlocking or inactive position. Accordingly, when either of the slides M is depressed, its cam surfaces positively turn the corresponding pair of rock shafts J to 90 locking or active position, and when the slide is elevated, the cam surfaces allow the rock shafts to be moved to unlocking or inactive position by the springs J^1 . The depression of the slides is effected by means of 95 a pair of font selecting keys or push rods M^4 arranged to operate a corresponding pair of pivoted bell crank levers M^3 connected to the slides through the medium of rods or links M^2 ; while the elevation of the slides is 100 effected by means of springs M^5 pulling upwardly on the rods M^2 and coming into play when the selecting keys are released.

The bell crank levers M^3 are formed with 110 downwardly extending arms or projections M^6 adapted to coöperate with beveled hooks O^1 of a horizontal spring-actuated locking plate O (see Figs. 4 and 5). The arrangement is such that when either one of the levers is operated, its downward projection 115 first engages the beveled portion of the corresponding hook and displaces the locking plate to one side to allow the projection to pass the hook, which is then immediately snapped across it to hold the lever in its 120 operated position, the displacement of the locking plate also releasing the other bell crank lever if the latter had previously been operated. It is seen, therefore, that the alternate actuation of the finger keys M^4 effects 125 the reverse movements of the two slides M , one being depressed to move the corresponding pair of rock shafts to active position, and the other elevated to allow the second pair of rock shafts to be moved to inac- 130

tive position, thus effecting the operative connection of the keyboard H to either pair of magazines to the exclusion of the other, so that matrices of one font only will be released upon the actuation of the keyboard.

As in my prior Letters Patent before mentioned, the major portion of the assembling devices for the main magazines A, including the raceway A² and the shiftable frame 10 therein, is mounted upon and carried by a swinging frame N which is arranged to turn about a vertical pivot rod N¹, so as to be swung outwardly away from the magazines to give access thereto or to the interior parts. 15 Similarly, the assembling devices for the supplemental magazines C, including the throats E, pulleys F, tubes G, keyboard H, font selecting keys M⁴, with their various appurtenant parts, and in fact all of the assembling devices immediately associated 20 with the magazines, are carried by a supplemental supporting frame N² which is also mounted upon the vertical pivot rod N¹. The two supporting frames N and N², therefore, are capable, independently or 25 jointly, of being moved from their operative position about the pivot rod N¹, which is common to both frames. As shown in Fig. 2, the pivot rod N¹ is carried at the forward 30 end of an arm N³ projecting from and rigidly secured to the rod N⁴ which has heretofore served as the pivot for the assembling devices of the main magazines.

It is to be noted that many of the features 35 of construction which have been described in connection with the supplemental magazines might be embodied to advantage in a machine equipped with but one series of magazines, either supplemental or main, or 40 in any other machine to which the improvements could be applied, and it should therefore be understood that they are not limited in their employment to the particular type of machine herein illustrated and described, 45 although they play an important part in connection therewith.

As previously stated, I have shown my invention merely in preferred form and by way of example, and it will be obvious that 50 many modifications and alterations therein and in its mode of application will suggest themselves to those skilled in the art without departure from its scope.

Having thus described my invention, its 55 construction and mode of operation, what I claim and desire to secure by Letters Patent of the United States, is as follows:

1. In a typographical machine, the combination of two series of matrix magazines, 60 distributing mechanism co-operating continuously with all the magazines of both series, two separate keyboards, one for each series, and means for operatively connecting said keyboards to different selected magazines of the respective series, whereby mat-

rices may be drawn from different magazines of either series alone, or of both series simultaneously, and mixed together in the same line.

2. In a typographical machine, the combination of two series of matrix magazines arranged side by side or in tandem, a plurality of distributers, each co-operating continuously with the opposite magazines of the two series, two separate keyboards, one for each series, and means whereby said keyboards may be operatively connected to different selected magazines of the respective series. 70

3. In a typographical machine, the combination with two series of matrix magazines arranged side by side or in tandem, two separate keyboards, one for each series, and means whereby said keyboard may be operatively connected to different selected 80 magazines of the respective series, of a plurality of character-distributers each co-operating continuously with the opposite magazines of the two series, and a primary distributor for delivering the matrices of the various magazines to one or another of the character-distributers according to form. 90

4. In a typographical machine, the combination of two series of matrix magazines arranged side by side or in tandem, a plurality of character-distributers each co-operating continuously with the opposite magazines of the two series, and a primary distributor for delivering the matrices of the various magazines to one or another of the character-distributers according to form. 95

5. In a typographical machine, the combination of a series of main matrix magazines, a series of supplemental matrix magazines arranged at the side thereof, a main 105 assembling belt onto which the matrices from all of the main magazines are delivered and extended so as to receive the matrices from the lowermost one of the supplemental magazines, and a separate and independent belt arranged in position to receive matrices from an upper one of the supplemental magazines and discharge them onto the main belt. 110

6. In a typographical machine, the combination with a series of main matrix magazines and a main assembling belt onto which the matrices therefrom are delivered, of a plurality of supplemental matrix magazines arranged at the side of the main magazines, 120 and a corresponding plurality of separate and independent belts adapted to receive the matrices from their respective supplemental magazines and deliver them onto the main assembling belt. 115

7. In a typographical machine, the combination of a series of main matrix magazines, a series of supplemental matrix magazines arranged at the side thereof, a main assembling belt onto which the matrices from 125

65 130

the main magazines are delivered and extended so as to receive the matrices from the lowermost one of the supplemental magazines, a separate and independent belt onto which matrices from an upper one of the supplemental magazines are delivered, and a tube or chute for conducting the matrices from the supplemental belt to the main belt.

8. In a typographical machine, the combination of a series of main matrix magazines, a series of supplemental matrix magazines arranged at the side thereof, a channeled raceway common to all of the main magazines and adapted to receive the matrices therefrom, a main assembling belt onto which the matrices from the raceway are delivered, short channeled throats to receive the matrices from the several supplemental magazines, the lowermost throat discharging its matrices directly onto an extended portion of the main assembling belt, and a separate and independent belt to receive the matrices from each remaining throat and discharge them onto the main assembling belt.

9. In a typographical machine, the combination of a plurality of matrix magazines arranged one above another in series, a main assembling belt onto which the matrices from the lower magazine are delivered, and a separate and independent belt overlying the main belt in position to receive the matrices from an upper magazine and discharge them onto said main belt.

10. In a typographical machine, the combination of a plurality of superposed matrix magazines, and a corresponding plurality of assembling belts, arranged one above another and in position to receive the matrices from the respective magazines, each overlying belt being sufficiently spaced from the underlying one to avoid interference with the matrices passing to the latter.

11. In a typographical machine, the combination of a plurality of superposed matrix magazines, a corresponding plurality of endless assembling belts arranged one above another in position to receive the matrices from the respective magazines, and a system of guide rollers to maintain the opposed stretches of an overlying belt out of contact but in immediate proximity to each other so as to afford sufficient clearance for the matrices passing onto the underlying belt.

12. In a typographical machine, the combination of a matrix magazine, an endless assembling belt to receive the matrices therefrom, a pair of rollers upon which it is supported, and a second pair of guide rollers over which the lower stretch of the belt passes, the said guide rollers being arranged between and adjacent the supporting rollers and having their axes slightly displaced from the axes of the supporting rollers in such manner as to maintain the opposed

stretches of the belt out of contact but in close proximity to each other, in the manner and for the purpose described.

13. In a typographical machine, the combination of an inclined matrix magazine, and an endless assembling belt disposed horizontally along the discharge end of the magazine and having both of its opposed stretches located substantially in its plane of inclination. 75

14. In a typographical machine, the combination of an inclined matrix magazine, an endless assembling belt disposed horizontally along the discharge end of the magazine and having both of its opposed stretches located substantially in its plane of inclination, and a short intermediate throat for conducting the matrices from the magazine to the assembling belt. 80

15. In a typographical machine, the combination of a plurality of inclined superposed matrix magazines, and a corresponding plurality of horizontally disposed assembling belts supported one above another in position to receive the matrices from the respective magazines, each overlying belt being located above the plane of inclination of the magazine served by the underlying belt, so as to avoid interference with the matrices passing from that magazine. 90

16. In a typographical machine, the combination of a series of matrix magazines each provided with escapements to control the release of the matrices therefrom, separate assembling belts to receive the matrices from the respective magazines, and a common series of actuating reeds connected to the escapements of all the magazines, the said reeds being arranged in advance of the assembling belts so as to be free and clear 100 of the matrices passing thereto. 105

17. In a typographical machine, the combination of a plurality of superposed inclined matrix magazines, a corresponding plurality of superposed assembling belts disposed along the discharge ends of the respective magazines, short channeled throats for conducting the matrices from the magazines to their respective assembling belts, and escapement operating means including a series 110 of key controlled reeds disposed vertically in front of the assembling belts, and series of pivoted levers connecting the reeds with the escapements of the several magazines, the levers of each series being pivoted below the 115 corresponding belt and throat, in the manner and for the purpose described.

18. In a typographical machine, the combination of a matrix magazine provided with escapements to control the release of the matrices therefrom, an assembling belt onto which the matrices are delivered, and means for operating the escapements, the said means including a series of actuating reeds located in advance of the assembling 125 130

- belt, and intermediate levers located beneath the belt for connecting the reeds with the escapements of the magazine; whereby the matrices are allowed to pass from the magazine to their place of assemblage in a path unobstructed by the escapement actuating devices. 5
19. In a typographical machine, the combination of two parallel matrix magazines each having a series of escapements, the said magazines being offset edgewise with respect to each other to stagger their escapements, and a series of escapement actuating devices arranged side by side and divided 10 into sets, one for each magazine, the actuating devices of one set being alternated with those of another set to correspond to the staggered relation of the escapements. 15
20. In a typographical machine, two parallel magazines each having a series of matrix channels, one of said magazines being offset edgewise with respect to the other to locate their channels in staggered relation. 20
21. In a typographical machine the combination of a series of parallel matrix magazines divided into pairs and each provided with a series of escapements, the magazines of each pair being offset edgewise with respect to each other to stagger their escapements, and a common series of escapement actuating devices arranged side by side and divided 25 into sets, the actuating devices of one set being alternated with those of another set to correspond to the staggered relation of the escapements of the several pairs of magazines. 30
22. In a typographical machine, the combination of a plurality of matrix magazines each having a series of escapements and divided 35 into pairs, each pair having the escapements of one of its magazines staggered with relation to those of the other magazine, and a common series of actuating reeds divided into sets appropriate to the escapements of either pair of magazines. 40
23. In a typographical machine, the combination of a plurality of matrix magazines each having a series of escapements and divided 45 into pairs, a common series of actuating reeds divided into sets, each constantly connected with the escapements of the corresponding magazines of the different pairs, and means for locking or unlocking the matrices in any selected pair of magazines to 50 prevent or permit their release therefrom when the escapement actuating reeds are operated. 55
24. In a typographical machine, the combination of a plurality of matrix magazines each having a series of escapements and divided 60 into pairs, a common series of actuating reeds divided into sets, each constantly connected with the escapements of the corresponding magazines of the different pairs, and matrix locking devices, one for each magazine. 65
25. In a typographical machine, the combination of a plurality of matrix magazines each having a series of escapements and divided 70 into pairs, a common series of actuating reeds divided into sets, each constantly connected with the escapements of the corresponding magazines of the different pairs, a matrix locking device for each magazine, and selecting keys or devices, one for each pair of magazines connected to the locking devices thereof. 75
26. In a typographical machine, the combination of a plurality of matrix magazines each having a series of escapements and divided 80 into pairs, a common series of actuating reeds divided into sets, each constantly connected with the escapements of the corresponding magazines of the different pairs, a matrix locking device for each magazine, selecting keys or devices, one for each pair of magazines, and means whereby the operation of one selecting key effects the movement of the matrix locking devices of one pair of magazines to inactive position and 85 simultaneously restores the matrix locking devices of another pair or pairs to active position. 90
27. In a typographical machine, the combination of a plurality of matrix magazines each provided with a matrix locking device, and divided 95 into pairs, and means for moving the locking devices of any selected pair of magazines simultaneously to active or inactive position, as required. 100
28. In a typographical machine, the combination of a plurality of matrix magazines each provided with a matrix locking device and divided into pairs, means for moving the locking devices of any selected pair of magazines simultaneously to active or inactive position as required, and means whereby the movement of one pair of locking devices to inactive position effects the movement of the other pair or pairs to active position. 105
29. In a typographical machine, the combination of a main magazine, a supplemental magazine arranged at the side thereof, assembling devices coöperating with each 110 magazine, and separate supporting frames upon which the assembling devices of the respective magazines are mounted, each of said supporting frames being movable independently from its operative position to 115 give access to the corresponding magazine or the interior parts. 120
30. In a typographical machine, the combination of a main magazine, a supplemental magazine arranged at the side thereof, 125

assembling devices coöperating with each magazine, and separate supporting frames upon which the assembling devices of the respective magazines are mounted, the said 5 supporting frames arranged to turn about a common pivot.

31. In a typographical machine, the combination of a main matrix magazine, a supplemental matrix magazine arranged at the 10 side thereof, assembling devices coöperating with each magazine, and a pivoted supporting frame upon which the assembling devices for the supplemental magazine are mounted whereby they may be carried out 15 wardly away from the magazine to give access thereto or to the other parts.

32. In a typographical machine, the combination with a matrix magazine provided 20 with escapements, matrix conveying mechanism coöperating with the magazine, escapement operating devices, and a keyboard connected thereto, of a movable supporting frame carrying said keyboard, escapement operating devices and matrix conveying 25 mechanism in their entirety.

33. In a typographical machine, the combination of two series of magazines, a sepa- 30

rate keyboard for each series, means whereby one keyboard may be connected to any selected one of the magazines of its corresponding series, and means whereby the other keyboard may be connected to different selected pairs of magazines of its series, for the purpose described. 35

34. In a typographical machine, the combination of a series of superposed matrix magazines, each having a series of escapements and divided into pairs, separate assembling belts to receive the matrices from the respective magazines, a common series 40 of actuating reeds located in advance of the assembling belts and divided into sets, each constantly connected with the escapements of the corresponding magazines of the different pairs, matrix locking devices, one for 45 each magazine, and font selecting means for moving the locking devices of one or another pair of magazines to inactive position to permit the release of matrices therefrom when the escapement actuating reeds are 50 operated.

In testimony whereof, I have affixed my signature.

JOHN R. ROGERS.
